UNITED STATES PATENT OFFICE

LEE HALL, OF ST. PAUL, MINNESOTA

PRESERVING GAME AND FOOD CARRIER

Application filed June 8, 1928. Serial No. 283,985.

The present invention relates to a preserving game and food carrier.

In the taking of game or fish, the sportsman is frequently at a considerable distance from home, and where a hunting or fishing trip lasts two or three days, the preserving of the game becomes a serious problem. Even where a cooler, such as a small refrigerator, is available, the game, especially in the case of wild fowl and small game such as rabbits and squirrels, has a tendency to heat and spoil where the game is packed in a single compartment.

An object of the present invention is to make a game carrier having compartments therein formed by division members of material which will permit a free circulation of air around the contents of said compartments, and having a covering of porous material.

In order to attain this object, there is provided, in accordance with one feature of the invention, a frame having vertical and horizontal partitions therein to divide the interior into compartments and having a covering of canvas with pockets sewn to the covering near the upper end thereof for holding ice or water soaked material, so as to permit the water from the melting ice or from the evaporation thereof to cool the contents of the carrier.

These and other features of the invention will be more fully brought out in the following description and the accompanying drawings, wherein:

Figure 1 is a view in perspective of the device, with the cover open.

Figure 2 is a view, also in perspective, of a portion of the case showing the method of retaining it in a closed position.

Figure 3 is a view, also in perspective, of the wire frame work of the device.

Figure 4 is a view in perspective of the device in closed position, showing one of the pockets for the refrigerating material open, and

Figure 5 is a view in elevation of a sheet of perforated material which may be used instead of wire mesh for covering the case and making the division members.

Referring to the drawings in detail, a wire frame A is preferably employed having a pair of rectangularly formed wire frame members 1 and 2 connected to each other at their corners by transverse wire frame members 3. A carrying handle 4 is connected to transverse frame members 5 and 6 by wire support members 7. A rectangular cover-frame member 8 is hingedly connected to the frame member 2 by means of hinge links 9 and 10. The entire frame work thus formed is covered by suitable material, such as wire mesh to form a covering which is rigid but which will permit a free circulation of air through the device. The interior of the device is divided into compartments by vertical partition members 11 and transverse partition members 12 spaced to form compartments of a required size. If desired, the horizontal partition members may be made 70 adjustable by supporting them upon suitable pins or strips, not shown, connected to the vertical partition members in a well known manner. By making the horizontal partition members removable it would permit the horizontal shelves to be removed so as to make the case more suitable for carrying food and expendable supplies, such as shot gun shells when going to the hunting grounds, and, as these supplies are expended during the trip, the horizontal shelves could be positioned as required to accommodate the game, as taken. The device is provided with a cover 13 of canvas or other porous material, such as felt, and a plurality of pockets 14 are secured to the canvas covering near the top of the device. The pockets are covered by flaps 15 secured as by snap fasteners 16 and are preferably made rather full so as to permit a comparatively large quantity of refrigerating material to be placed therein.

When it is desired to use the device as food or game preserver, the pockets may be filled with ice or water soaked cloths, leaves, or other material which will permit a gradual absorption of the water by the porous covering. Capillary action will cause a gradual absorption of the water from the melting ice or the water soaked material in the pockets throughout practically the entire area of the 100

canvas covering, and the evaporation of this moisture will cool the contents of the carrier. The wire mesh forming the covering of the device and the partition walls therein will permit a free circulation of air about the contents of the compartments. The device may be suspended from a tree while in camp or placed upon the running board of an automobile, or stored in the baggage compartment of a train during transit. The fabric covering forms a protection against flies and other insects which is a frequent cause of food and game spoilage.

Instead of wire mesh for the covering and division member material, perforated sheet metal 17, as illustrated in Figure 5, may be employed. If desired, the fabric covering 13, instead of being permanently secured to the device, may be made removable and may 20 either be secured to the frame by means of snap fasteners in a well known manner, or may be made to fit tightly thereon so that no fastening means are required to hold it in place. A flap 18 having fastening means such 25 as snap fasteners 19 secured thereto may be employed to hold the cover closed.

I claim:

1. A carrier cooler of the class described comprising a rigid ventilated casing having 30 a plurality of open work upright partitions and connecting open work shelves extending from front to rear of said casing, a door hinged to the bottom of the front side of said casing, a porous water absorbent covering for said hinged side of the casing, a second porous water absorbent covering for the end walls of said casing, a water pocket secured to the upper portion of the covering of said side of said casing and water pockets 40 secured to the upper portion of the end walls of said casing.

2. A carrier cooler of the class described comprising a rectangular oblong casing with a top covering having a handle, said cooler having a plurality of rigid partitions and shelves extending from front to rear of the cooler and forming compartments, a door forming one side of said casing, a liquid absorbent covering for the end and side walls 50 and door of said casing, and a plurality of pockets secured to the upper portions of the absorbent covering of said side and end walls and door to permit any liquid contents of said pockets being absorbed by said wall and door covering.

In testimony whereof I affix my signature.
LEE HALL.
